(57) **CLAIM**

The ornamental design for a vehicle transponder holder, as shown and described.

DESCRIPTION

FIG. 1 is a front plan view of a vehicle transponder holder showing my new design;

FIG. 2 is a left view thereof;

FIG. 3 is a top view thereof;

FIG. 4 is a rear view thereof;

FIG. 5 is a right view thereof; and,

FIG. 6 is a bottom view of my instant invention.

The broken lines are for environmental purposes only and form no part of the claimed design.
